(57) **CLAIM**

We claim the ornamental design for a pressure gauge housing, as shown and described.

DESCRIPTION

FIG. 1 is a perspective upper view of the pressure gauge housing showing our novel design;

FIG. 2 is a perspective lower view thereof;

FIGS. 3 and 4 are rear and front elevation views thereof, respectively;

FIGS. 5 and 6 are left and right side elevation views thereof, respectively;

FIG. 7 is a bottom plan view thereof; and

FIG. 8 is top plan view thereof;

FIG. 9 is a perspective upper view of an alternative embodiment of the pressure gauge housing showing our novel design;

FIG. 10 is a perspective lower view thereof;

FIGS. 11 and 12 are rear and front elevation views thereof, respectively;

FIGS. 13 and 14 are left and right side elevation views thereof, respectively;

FIG. 15 is a bottom plan view thereof; and,

FIG. 16 is top plan view thereof.

The broken lines shown represent unclaimed subject matter and form no part of the claimed design.
